UNITED STATES PATENT OFFICE.

PHILO SCOTT, OF FINE, NEW YORK.

RAILWAY-SWITCH.

No. 836,146.

Specification of Letters Patent.

Patented Nov. 20, 1906.

Application filed June 15, 1906. Serial No. 321,796.

To all whom it may concern:

Be it known that I, PHILO SCOTT, a citizen of the United States, residing at Fine, in the county of St. Lawrence and State of New York, have invented certain new and useful Improvements in Railway-Switches, of which the following is a specification.

This invention relates to improvements in switches designed for use in connection with railroad-tracks; and the invention relates particularly to a switch wherein the movable switch-tongues and their related parts are so constructed and applied that they may be moved and maintained in either open or closed position as if made of a single part.

The object of the invention is to provide a railway-switch in which the movable members, especially the tongues or pointed rails, are held rigidly in place and prevented from becoming loosened by reason of the wear, strain, or vibration caused by passing trains; and a particular object is to provide simple but powerful means for bracing and holding the thin or sharp points of said switch-tongues from being sprung or jarred out of line or place during the passage of trains over said switch; and a further object is to provide means for readily and quickly adjusting certain parts of the switch, the said switch being adapted for connection with and operation by any of the well-known switch-throwing levers or stands.

Other features and objects of the invention will be fully understood from the detail description which follows, reference being had to the accompanying drawings, forming a part of this specification, and in which—

Figure 1 is a plan view of my improved switch, showing the manner of constructing and applying the same in connection with the track-rails. Fig. 2 is a side elevation showing the switch-operating parts. Fig. 3 is a cross-section substantially on the line *a a* of Fig. 1, showing the manner of bracing and tying the points of the switch-tongues. Fig. 4 is a cross-section substantially on the line *x x* of Fig. 1, showing adjustable means for securing the switch-rails to one of the tie bars or plates. Fig. 5 is a detail of one of the clamping-dogs and wedges.

Similar reference-numerals are assigned to corresponding parts throughout the several views.

In the drawings, 2 represents the cross-ties upon which are laid the continuous or permanent track-rails 3, the latter having no direct connection with the switch members.

4 represent the rails forming a continuation of the movable switch-tongues or rails 5 and 6, which are joined to the rails 4 by means of the fish-plates 7. Any other suitable connecting means may be employed for connecting the tongues to rails 4. The lateral movable play of the switch-tongues 5 and 6 being very slight, not over two or three inches at their free ends or points, the said fish-plates will permit of the operation of the switch-tongues without any other form of pivot or hinge connection than that shown in Fig. 1. The switch-tongues 5 and 6 have a sliding bearing on the upper face or side of the cross-ties 2, which serve to keep them in level position with reference to the main or rigid track-rails. Tongues 5 and 6 are bolted or otherwise rigidly secured to a series of flat steel or iron bars which are disposed between 75 and extend across the road-bed parallel to the ties 2. The most important of these metallic tie-bars 8 is preferably made in the form of an elongated horseshoe, the arms of which are made long enough to engage and bear against the under side of the two outer track-rails 3.

9 represents another flat metal bar which also extends across and under the tracks 3, and it is disposed between the arms of bar 8. 85 Bar 9 is securely bolted to the curved portion of bar 8, where it lies in an angle or recess 10, provided for the purpose of bringing the said bars to a common level beneath the several rails. These two bars are therefore tied together and capable of being moved as one part. Bar 9 and one arm of bar 8 are directly connected to the switch-tongues 5 and 6, by means of a series of metallic fasteners or rail-braces 11 (shown in Fig. 1) in such a manner that when bar 9, which is intended to be connected with any suitable switch-throwing stand or lever, is moved to right or left, it causes the opening or the closing of said switch by a corresponding movement of tongues 5 and 6. One end of bar 9 is provided with a hole or slot 12 for use in connecting it with a switch-stand or lever.

13 represents a third metallic bar disposed

beneath and connected to tongues 5 and 6 near their inner ends. This bar or tie-plate is intended to assist the other bars in moving, as well as holding, the tongues in true level 5 position and parallel with each other, and it also extends for some distance beyond the rails 3 in order to prevent the tongues from being lifted above the level of the track-rails. Switch-tongues 5 and 6 are connected 10 to bar 13 by means of a series of dogs or clamps 14, which are held in place and drawn tightly against the tongues by the keys or wedges 15. Dogs 14 pass through and are held from lateral movement by the slots 16, 15 formed in bar 13. This latter form of connection is provided to afford means for keeping these parts tightened up. In the old 20 style of switches bolts or rivets have been extensively employed to bind or secure the movable switch-tongues together, and the vibration caused by the passing of heavy trains over the switches has shown a constant tendency to loosen said parts, and often costly wrecks have resulted. With the key 25 and clamp connections shown and described herein, there is less liability of the said parts being shaken loose, and if they should become slack it is a very simple matter for the track-men to drive in the wedges or keys 15.

30 A large number of derailments and other serious accidents are constantly occurring at railway-switches due largely to the fact that the points of the switch-tongues, necessarily made slender and light, are not held 35 rigidly enough to prevent them from springing laterally or vibrating to such an extent that the flanges of the wheels of rapidly-moving trains causes the accidental opening and frequently the breaking of the switch- 40 tongues. In order to safely guard against all such mishaps, I have provided diagonal braces 17 and 18 substantially in the form of the letter "X" and have disposed them in such manner that one end of each brace 45 bears against the side of the thin point of the tongue, and each brace is then secured to the bars 8 and 9 by means of the bolts 19, while the opposite ends of said braces are secured to the central portion of the tongues. Under 50 this form of bracing it is practically impossible for the free ends or points of the tongues 5 and 6 to vibrate or otherwise move unless operated by the switch-throwing means, which may be connected with the bar 9. Diagonal braces 17 and 18 where they cross each other are also bolted together, as shown 55 in Fig. 1. In order to make the tongue-points still more rigid and unyielding when the switch is set in either position, I have 60 provided a transverse brace 20, preferably made of metal in the form shown in Figs. 1 and 2. This brace is bolted to the outer ends of braces 17 and 18 and also to the ex-

treme end or point of each of the tongues 5 and 6. Under the herein-described plan or 65 form of bracing, taken with the connections between the bars 8 and 9 and the switch-tongues, all of the movable parts of my switch may be shifted or held in any desired position without in any way endangering 70 the safe passage of trains, whether the switch is open or closed.

It is obvious that the form and arrangement of the various parts of my invention may be modified or changed within the scope 75 defined by the appended claims without departing from the spirit of my invention.

Having thus described my invention, what I claim as new, and desire to secure by Let- 80 ters Patent, is—

1. In a railway-switch, the combination with a pair of switch-tongues, of a series of metallic bars secured to said switch-tongues, one of said bars being formed like a horse-shoe, the other bars being substantially 85 straight, a pair of diagonal braces connected to said tongues and also to two of said bars, and a transverse brace connected to the points of said switch-tongues and to the outer ends of said diagonal braces, substan- 90 tially as described.

2. In a railway-switch, the combination with the track-rails and a pair of movable switch-tongues disposed between said track-rails, of a series of metallic tie-bars connected 95 to said switch-tongues and disposed underneath said track-rails and said tongues, a pair of diagonal braces mounted upon said tie-bars between said switch-tongues adapted to hold said bars and tongues rigidly together, 100 a transverse brace disposed between and connected to the points of said switch-tongues and also connected to said diagonal braces, and a series of dogs and keys for connecting one of said tie-bars to said switch-tongues. 105

3. In a railway-switch, the combination with a pair of switch-tongues disposed between permanent track-rails, of a plurality of tie-bars extending across the road-bed beneath said track-rails and said switch-tongues adapted to hold said switch-tongues in level and parallel position and to effect the opening and closing of said switch, diagonal braces secured to the upper sides of two of said tie-bars and also secured to said switch-tongues, 110 a transverse brace connected with the points of said switch-tongues and with the outer ends of said diagonal braces, adjustable means, comprising a series of dogs or clamps and wedges for connecting said switch-tongues to one of said tie-bars and means for connecting one of said tie-bars with a switch-operating stand or lever. 115

4. In a railway-switch, the combination with the track-rails and a pair of movable switch-tongues, of a series of bars disposed 120

beneath said rails and tongues, means for connecting said bars to said tongues, means for connecting two of said bars with each other, a pair of crossed braces connected with said tongues and with two of said bars, a transverse brace connected to said crossed braces and also to the points of said tongues, means for connecting said tongues with the fixed rails of a siding or main line, and means

for connecting said tongues with a switch-operating mechanism, substantially as described.

In testimony whereof I affix my signature in presence of two witnesses.

PHILO SCOTT.
